CLAIM

The ornamental design for a speaker, as shown and
described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front, right perspective view of a first embodiment of a speaker showing our new design;

FIG. 2 is a front left perspective view thereof; and,

FIG. 3 is a front elevational view thereof.

The broken lines illustrating part of the speaker form no part
of the claimed design.

1 Claim, 3 Drawing Sheets
(3 of 3 Drawing Sheet(s) Filed in Color)
